SPORTS FISHING BELT

Anthony M. Vanus, 105 Brown Drive,
Claremont, Calif. 91711

Filed Nov. 4, 1974, Ser. No. 520,367

Term of patent 14 years

Int. Cl. D2—07

U.S. Cl. D2—381

FIG. 1 is a right front perspective view of a sports fishing belt showing my new design;

FIG. 2 is a left side elevational view thereof; and
FIG. 3 is a bottom plan view thereof.

I claim:

The ornamental design for a sports fishing belt, as shown and described.
